[57] CLAIM

The ornamental design for a tilting maze game, as shown and described.

DESCRIPTION

FIG. 1 is a perspective view of a tilting maze game showing my new design;

FIG. 2 is a front elevational view thereof, the rear and all other sides each being a mirror image of the front shown in FIG. 2;

FIG. 3 is a top plan view thereof; and,

FIG. 4 is a bottom view thereof.

FIG. 1

FIG. 3.

FIG. 2.

FIG. 4
